UNITED STATES PATENT OFFICE.

HERMAN MCCLELLAN, OF CINCINNATI, OHIO.

BEARING FOR PIANO-STRINGS.

SPECIFICATION forming part of Letters Patent No. 703,708, dated July 1, 1902.

Application filed November 6, 1899. Serial No. 735,885. (No model.)

To all whom it may concern:

Be it known that I, HERMAN MCCLELLAN, a citizen of the Dominion of Canada, and a resident of the city of Cincinnati, in the county 5 of Hamilton and State of Ohio, have invented certain new and useful Improvements in Bearings for Piano-Strings, of which the following is a specification.

The strings of the piano are strained upon 10 a common frame. One end of each string is connected to a hitch-pin and the other end to what is known as a "tuning-pin." This tuning-pin can be turned, and being turned in one direction winds up the string and tight- 15 ens and strains it. Being turned in the opposite direction, it lessens the strain upon the string. In this manner the desired and requisite musical pitch is imparted to the string. On that part of the frame where the 20 tuning or wrest pin is located and toward the mid-length of the string is a bearing on which the string rests. This bearing we will denominate the "wrest-block" or "plate" bearing. Between these two bearings and nearer 25 the tuning-pin bearing is another bearing, which may be termed the "capo-tasto" bearing and which depresses or pushes the string in a direction opposite to that in which it is pushed by the wrest-plate bearing afore- 30 named. This capo-tasto bearing is nearer to the tuning-pin bearing than it is to the hitch-pin. That part of the string which is between the capo-tasto bearing and the hitch-pin is the part which vibrates and gives the 35 musical sound or note. Near this capo-tasto bearing, but between it and the hitch-pin, is the hammer which strikes the string and causes the vibration of the latter.

The advance in the construction of pianos 40 has been marked by the introduction of metal frames for supporting the wires, and the latter are strained upon these in the manner aforesaid. In process of time in successive pianos the wires have been more and more drawn or 45 strained. There are usually three wires or strings to a given note, and as a consequence the present modern piano-frames are subject- 50 ed to a strain amounting to tons. The capo-tasto bearing aforesaid, originally made of wood, has been made of iron integral with the large iron frame or plate and cast with it in order to prevent, first, the pull of the

wires, and, secondly, their vibration from cutting into it and grooving it. If cut into, the wires would sink into the grooves so cut and 55 their tension would be changed and their pitch as a musical note would be altered. The sides of the grooves and the bearing on the bottom of the grooves, much longer than the original edge of the bearing, would also 60 clog and alter to an extent the vibration of the strings; but the employment of an iron bearing at this point is accompanied with a marked disadvantage. The vibration of the strings at and against the iron bearing im- 65 parts a metallic twang to the note produced by the string or strings, and thus injures the purity of the musical note. What is true in this regard of one note is true of all.

The object of my invention is to obviate 70 this metallic twang and restore each note to its perfect purity and to preserve its original clearness of tone. This object I accomplish by means of the advantageous construction which I will now describe. 75

In the accompanying drawings, making a part of this application and in which similar letters of reference indicate corresponding parts, Figure 1 represents, on a scale diminished from the ordinary size, a section 80 taken parallel to the wires and of my improved bearing and shows in elevation a musical string in position and the hitch-pin and tuning-pin to which it is connected and the wrest-plate bearing, also a hammer and its 85 immediate connections. Fig. 2 represents a view, somewhat enlarged over the preceding figure, of the under side of my improved iron bearing, a portion of the lower portion of the bearing being broken away to further 90 illustrate the construction of the bearing. This view shows three strings crossing the bearing, the end portions of the strings being omitted as unnecessary to the understanding of this figure and to insure compactness. 95

In the drawings, A indicates the iron main frame or plate.

B indicates one of the strings. Usually three unison-strings are grouped together to form the means for making a given note. A 100 single string would produce the note, but the addition of two more strings confers additional volume and richness of tone. The string is connected at one end to the hitch-

pin B³ and at the other end to the tuning-pin B². The string passes from the tuning-pin B² onto the wrest-plate bearing B⁴ and then passes down and against the bottom of the 5 capo-tasto bearing C, and thence extends to the sounding-board bridge B⁵ and hitch-pin. B⁶ indicates part of the sounding-board.

Below and to the right of the capo-tasto bearing in Fig. 1 is seen one of the hammers 10 in impingement with a string B. The hammer is made in any suitable manner. The one shown is composed of the head H³, surrounded by the usual felt or soft portion H². It is this felt portion H² which comes into contact with the strings. This head H³ is connected to a shank H⁴. The capo-tasto bearing-bar C and its component parts are the subject of my present invention. One of the component parts of this bearing C is the foundation-piece D. This foundation-piece will ordinarily be made of a suitable metal. Of the metals I prefer iron as the material for this foundation-piece. The latter is duly supported at or near each end by a suitable brace. 15 One of such braces K is shown in Fig. 1. The lower portion of the foundation-piece D is recessed, forming a recess D². Another component portion of this bearing is the wooden portion E, received into the recess D² and secured therein. This portion E has in its lower and central portion a recess E². Into the latter extends the tongue or rib F² of an aluminium bearing F. This latter bearing has shoulders F³, which rest upon the lower portions of the wooden bearing E. The under side of the aluminium bearing gradually narrows down and comes at bottom to a narrow ridge F⁴. On this ridge the wires or strings rest, substantially as shown. The aluminium 20 bearing is a strong tough metal, which well resists any tendency of the wires pressing against it and under severe strain from cutting into it or in any wise grooving it. The vibration of the aluminium, so far as it is perceptible, is pure and soft and does not impart a metallic ring or ringing sound to the wires impinging it, such as is usual in the iron bearing. This aluminium bearing, being

mounted on a wooden support intervened between it and the iron supporting portion 50 above, cannot transmit the vibration of the string or strings to the iron bar D and frame K above. Thus there is practically no vibration of the iron frame or plate and the vibration of the strings is free from metallic ring- 55 sounds.

By my invention the full singing quality of the tone is retained and secured.

The advantages of my invention are obvious from the foregoing description. 60

Before reciting the claims I desire it to be noted that the shoulders F³ should always be out of contact with the metal piece D, that the formative means whereby the constituent parts of the bearing are united may be varied without departing from the main features of my invention.

My invention is shown in connection with a grand piano; but it is applicable to any piano.

What I claim as new and of my invention, 70 and desire to secure by Letters Patent, is—

1. For a piano, a wire bearing having a stiff foundation, provided with recess D², a bearing of material that does not yield or become grooved by the wires, and in so far as it vibrates, gives out a pure, soft tone, differentiated from the metallic ring of iron or steel, and which bearing has a ridge F⁴, and a rib or extension F², shoulders F³, piece E adapted to resist the transmission of sound, and having recess E² into which the rib F² is received, and the said piece E being received into the recess D² of the foundation, substantially as and for the purposes specified. 75

2. For a piano, a wire bearing having an 80 iron foundation provided with a recess D², a wooden bar E received therein and having a recess E², and an aluminium bearing, having a narrow bottom ridge E⁴, and a rib F² received into the recess E², substantially as and 85 for the purposes specified. 90

HERMAN McCLELLAN.
